UNITED STATES PATENT OFFICE.

MARTIN T. McDONOUGH, OF SUN, WEST VIRGINIA.

MEANS FOR PREVENTING MINE DISASTERS.

No. 903,492.

Specification of Letters Patent.

Patented Nov. 10, 1908.

Application filed April 21, 1908. Serial No. 428,468.

To all whom it may concern:

Be it known that I, MARTIN T. McDONOUGH, a citizen of Ireland, residing at Sun, in the county of Fayette and State of West Virginia, have invented certain new and useful Improvements in Means for Preventing Mine Disasters, of which the following is a specification, reference being had to the accompanying drawings.

10 This invention is an improved system of working coal and other mines and of ventilating the same.

The invention contemplates a mine having a main hauling way containing all electrical conductors, steam pipes and also the main tracks over which high speed motor cars travel without danger to the miners and without buffeting the air currents and without interfering with the ventilation of the mine; and it further contemplates, in connection with such main hauling way and with auxiliary hauling ways or passages for causing an effective circulation of pure air throughout all parts of the mine, a safety manway or passage co-extensive in length with the main hauling way and by means of which the miners or employees may go to and from the various working places throughout the mine in perfect safety, said safety manway being shut off from the other parts of the mine and being in communication with the main hauling way and the auxiliary hauling ways and air passages by means of suitable doors so that in the event 30 of an explosion or fire at any part of the mine the employees may quickly and easily enter the manway and pass safely out of the mine, said manway also permitting of ready and safe entrance to the mine by res- 40 cuing and fire fighting parties in the event of a disaster by fire or explosion.

The object of the invention is to provide an improved system of working and ventilation whereby loss of life and property due 45 to explosions and fires will be reduced to a minimum and whereby the mines may be worked to the fullest extent and all the coal removed therefrom without endangering life or wasting timber.

50 With the above and other objects in view as will hereinafter more fully appear, the invention consists in the novel features of construction, combination of elements and arrangement of parts set forth in the following specification and claims.

In the accompanying drawings, Figure 1

represents a horizontal section through the drive of a shaft mine embodying the invention; Fig. 2 is a vertical section through the shaft of such mine, such section being taken 60 on the plane indicated by the line 2—2 in Fig. 1; Fig. 3 is a detail vertical section taken on the plane indicated by the line 3—3 in Fig. 1 and showing one of the overcasts; Figs. 4 and 5 are detail views partly in section of one of the fire proof doors; Fig. 6 is a horizontal section through a drift mine embodying the invention; and Fig. 7 is a section in an inclined plane through a slope mine embodying the invention. 70

Referring more particularly to the drawings, 1 denotes the main hauling way, 2 the safety manway, and 3, 4 the auxiliary hauling and working ways which insure a continuous circulation of pure air through all of 75 the working places on each side of the mine. The hauling way 1 and manway 2 are parallel and arranged between the working ways 3, 4, but the manway crosses over the hauling way adjacent to two vertical shafts 5, 6 80 which extend from the surface to the hauling way 1 and manway 2 and form entries for the same. The main shaft 5 is adapted to contain the elevators and adjacent to one side is a vertical partition 7 which forms a 85 vertical air shaft 8.

9 denotes a fan of any suitable form and construction which may be reversed so that it can be used either for impelling air through the passage 8 of the portions of the 90 mine or exhausting air from the same. A vertical partition 10 is arranged in the shaft 6 which latter is located adjacent to the main shaft 5, and said partition 10 is adapted to form a vertical shaft or passage 11 at the 95 upper end of which is a suitable fan 12, preferably an impelling fan for impelling a blast of air through one side of the mine. The air shaft 11 forms an inlet for the ventilating current or blast on one side of the 100 mine, and the shaft 6 forms an outlet for a portion of such ventilating current, also for a ventilating current on the other side of the mine, the inlet of which is the air shaft 8. These ventilating currents pass through the 105 manway 2, the outlet of which latter is also formed by the shaft 6 and in order to permit the miners or employees to ascend said shaft one or more flights of stairs 13 are arranged within the same. 110

14 denotes a trap door arranged to cover the outlet shaft 6 in the event of a fire or

explosion within the mine, but which is kept normally in its open position as shown in full lines in Fig. 2. The portions of the ventilating currents that do not find their outlet through the manway and the shaft 6 have their outlet through the hauling way 1 and the main shaft 5 as hereinafter explained.

The passages 1, 2, 3, 4, as well as the other passages presently explained, are formed by tunneling which latter produces a partition or pillar 15 between the hauling way 1 and the manway 2 and similar partitions or pillars 16, 17 between the manway 2 and working way 3 and between the hauling way 1 and the working way 4, respectively. Extending outwardly from the partitions or main headings 16, 17 are cross headings or partitions 18, 19 which make the working ways 3, 4 zig-zag and divide the seam of coal or ore into working squares 20. The miners work into the squares 20 from the different portions of the working ways 3, 4 and owing to the shape of said ways and to the provision of the cross or butt headings 18, 19 therein, the ventilating currents will be caused to pass through all of the various working places to remove poisonous and explosive gases, dust and the like and to supply pure fresh air for the miners and animals. The working ways or passages 3, 4 are provided with tracks for the coal cars and mules may be used for hauling these cars to the main hauling way 1.

Doors 21 are provided in the partition 17 adjacent to each of the cross headings or partitions 19 to permit of access between the working way 4 and the hauling way 1. These doors open outwardly or away from the main hauling way 1 so as not to interfere with the rapid transit of motor cars and trains in said hauling way and they are preferably constructed and operated as shown in Figs. 4 and 5 of the drawings. The door 21 is made of metal and hinged at 22 to a metal frame 23 set in an opening in said partition. The door 21 is made self closing by attaching to it a steel cable 24 which passes over a guide pulley 25 and carries a weight 26. The guide 25 and weight 26 are arranged in a tubular metal post 27 having a point 28 at its lower end to be driven into the floor and a pointed fastening screw 29 at its upper end to be driven into the roof or ceiling. The points 28, 29 effectively retain the post in position and permit it to be turned so that the cable 24 will not bind. Doors 30, similar to doors 21, are arranged in each of the cross headings or partitions 18 adjacent to the partition 16. These doors are normally closed and are only opened to permit of the passage of persons or cars through them. Doors 31, similar to doors 21, are provided at intervals of about 500 feet in the partition 16 so that miners in any

of the working places in the working way or passage 3 may readily enter the manway 2. These doors are normally closed and open inwardly or into the manway 2 to prevent the miners from jamming against the same should they become panic stricken in the time of disaster. Doors 32, similar to doors 21, are arranged at intervals of about 500 feet in the partition 15 so that the miners in any of the working places in the working way or passage 4 may pass from the main hauling way 1 into the manway 2. These doors, similar to the doors 31, open inwardly into the manway.

At the lower end of the main shaft 5 is a vertical partition 33 containing openings through which the cars may be moved and placed upon the elevator cages. The main hauling way 1 extends to the partition 33 and in front of the latter, said hauling way is enlarged, as shown at 34, to permit of numerous tracks and switches for the convenient shifting and handling of the loaded cars. A space 35 is provided in each of the lower ends of the elevator shaft for the handling of empty cars and a by-pass or passage way 36 is provided between the front and rear spaces or chambers 34, 35 and around the elevator cages in order to permit the motor cars to readily pass to the rear of the mine and pick up the empty cars. A passage way 37 is provided adjacent to the partition 6 so that miners in the front part or chamber 34 may pass directly to the passage way 36 and around the elevators to the rear part or chamber 35 without passing through the elevator shaft and thereby endangering their lives. The loaded cars from the different portions of the working way 4 pass through the doors 21 and into the main hauling way 1 and then through the latter to the elevators, but the loaded cars on the other side of the mine in the working way 3 pass through the latter and the doors 30 and then into the main hauling way 1 through a door 38 which is similar to the doors 21. This door is normally closed and opens away from the main hauling way. The empty cars for this side of the mine pass from the rear part or chamber 35 through a passage way 40 and a door 41 arranged in the partition 18 nearest to the main shaft or elevator shaft. Said door 41 is similar to the door 21 and is normally closed.

In order to permit the ventilating currents to pass from the working way 4 into the manway 2, an overcast 42 is formed over the main hauling way adjacent to the inner end of the mine. This overcast is clearly shown in Fig. 3 and consists of a passage way of sufficient size for the ventilating current and also for the miners to pass from the working way 4 to the manway 2. Said overcast is formed by shooting passages or channels 43

upwardly and inwardly from opposite points in the passages 2, 4 to the top of the passage 1, then erecting walls of masonry 44 in such points of the passage way for the 5 support of metal beams 45 and metal flooring plates 46. Overcasts similar to the one shown in Fig. 3 are formed from time to time as the mine advances through the seam of coal, but only the one farthest from the 10 main shaft is kept open, the others being walled up with brick work or masonry as the mine is extended and a new overcast is made. In the mine shown in Fig. 1 the overcast 42 is open, while a similar overcast 15 47 which is used in the early stage of the working of the mine is closed, as indicated at 48.

In order to permit a portion of the ventilating current passing through the passage 20 4 to pass the overcast 42 and to the miners working at the extreme inner working places in said passage 4, a partition 49 is arranged adjacent to the overcast 42 so as to partially fill the passage way 4 at such point. This 25 partition is of such size as to permit a suitable quantity of the ventilating current to pass to the inner extremities of the passage 4 and the working places in the latter and such portion of the current finds its outlet 30 through a cut-through 50 formed in the partition 17. The cut-throughs or openings 50 are formed from time to time as the mine advances, but only the innermost one is kept open, the others being bricked up or closed 35 by a door similar to the doors 21 as a new one is made in the advance of the mine. The partition or deflect 49 is removed from the open or active overcast when the latter is closed and is similarly positioned at the 40 new or last made overcast.

51 denotes a cut-through or opening formed in the partition 16 for the purpose of permitting the ventilating current on the other side of the mine to pass through the 45 working way or passage 3 into the manway 2. Similar cut-throughs are formed at different points in the partition 16 as the mine advances, but only the innermost one is kept open, the others being bricked up or closed 50 by the doors 31 when a new one is made.

52 denotes an overcast at the point where the manway 2 crosses the main hauling way 1. This overcast extends diagonally or at 55 an angle from the main hauling way, but is similar in construction to the overcast shown in Fig. 3.

53 denotes a similar overcast in the passage way 3, at the lower end of the shaft 8. This overcast, as clearly shown in Fig. 2, 60 carries the ventilating current passing down the shaft 8 over the passage 40. By providing this overcast the ventilating current passing down the shaft 8 is prevented from passing directly to the rear portion or chamber 45 of the mine and is caused to take a

circuitous course through the working way or passage 4.

At the lower end of the air shaft 11 are two doors 54, 55. The door 54 is arranged in the partition 10 and is normally closed to 70 prevent the ventilating current passing down the shaft 10 from passing into the shaft 6 and the manway. The other door 55 is normally open and allows the ventilating current to pass into the working way or passage 4. 75

The operation of the invention is as follows: The two fans 9, 12 are constantly in motion impelling ventilating currents through the shafts 8, 11 and the two sides 80 of the mine. The current from the shaft 8 on one side of the mine passes in the direction of the full line arrows shown in Figs. 1 and 2, first through the overcast 53, then through all of the working places in the various parts of the working way or passage 3, then through the cut-through 51 into the manway 2, then back through the latter and through the overcast 52 and then out of the mine through the shaft 6. The ventilating 90 current upon the other side of the mine passes in the direction indicated by the full line arrows in Figs. 1 and 2, first through the door 55, then through all of the working places in the various portions of the working way or passage 4 until it reaches the partition or deflector 49, which latter divides it into two portions, one of which continues in the inner portion of the passage 4 and leaves the latter and enters the main hauling way 1 100 through the cut-through 50 and the other portion of which passes through the overcast 42 into the manway 2 and then out through the latter and the outlet shaft 6 as above explained. The portion of the current passing 105 through the overcast 50 continues through the main hauling way 1 to the main or elevator shaft 5 and escapes through the latter. In the event of explosion or fire in the mine the fan 9 is reversed to exhaust the air from 110 the shaft 8 and reverse the direction of the current of air through the adjacent side of the mine and the door 54 is opened and the door 55 closed so that the current on the other side of the mine, which current is produced 115 by the fan 12, will be reversed. These reversed currents are indicated by the dotted line arrows in Fig. 1.

From the foregoing it will be seen that the improved arrangement of parts insures an 120 effective circulation of fresh air through all of the working parts of the mine and that the circulation will be strong enough to carry out all of the poisonous gases, coal dust and the like so that the danger of explosion and fire 125 will be reduced to a minimum and the miners and employees of the mine will be supplied with pure air. The provision of the safety manway permits of ready and safe access to any part of the mine both in times of dis- 130

aster and when everything is in normal working condition. The various doors provided in it permit miners in any portion of the mine to quickly enter it and escape when there is any danger; and by reason of its isolation from the other parts of the mine it will not be affected by a fire or explosion in any part of either side of the mine and will consequently form a safe and direct outlet. Furthermore, it permits rescuing parties and fire fighting parties to enter the mine immediately after a fire or explosion, this being impossible in mines as operated at the present time. The provision of the main hauling way containing all of the electrical conductors, steam pipes, etc., and the main tracks for the rapid transit motor cars, effectively lessens the danger of accidents which so frequently occur when miners must pass through passageways containing such conductors, pipes and cars. Since this hauling way is not used as an inlet and outlet passage way for the miners, the cars may be run at high speed without danger and their movement in the passage way will not interfere with the effective ventilation of the mine. This plan of working mines also permits the pillars or partitions to be drawn without causing a crash or creep, and thereby preventing the waste of the coal forming such pillars or partitions.

In Fig. 6 of the drawings the invention is shown embodied in a drift mine, that is, one which is horizontally disposed in the side of a hill. This mine has the main hauling way 1^a, the manway 2^a, and the auxiliary hauling ways and working passages 3^a, 4^a. It is also similar in other respects to the embodiment of the invention shown in Fig. 1 with the following exceptions. The manway is straight and has an overcast 52^a, and at its inlet is a door 14^a. A reversible fan 3^a is arranged at the inlet of the passage 14^a, while an impelling fan 12^a is arranged at the inlet of the passage 3^a. A door 38^a is provided beneath the overcast 52^a for the passage extending under said overcast and affording communication between the passage 3^a and the main hauling way. Doors 54^a and 55^a are provided for the purpose of reversing the direction of the air current produced by the fan 12^a. 42^a and 47^a represent overcasts similar to the overcasts 42 and 47 and 49^a represents a partition similar to the partition 49. The remaining portion of this embodiment of the invention is similar to that of the one first described.

In Fig. 7 of the drawings the invention is shown embodied in a slope mine, that is, one that is inclined downwardly from the surface. This mine is very similar to the one shown in Fig. 1, but instead of having the vertical shafts at its mouth it has downwardly inclined shafts. 5^b denotes the main shaft containing steps 5^c and having an air

shaft 8^b upon one side. 1^b denotes the main hauling way, 2^b the manway, and 3^b and 4^b the auxiliary hauling ways and working passages. 6^b represents the outlet for the manway containing the steps 13^b and the air shaft 11^b. The construction of the other parts of this mine is similar to that of the corresponding parts of the mine shown in Fig. 1, and its operation will be readily understood from the foregoing description.

While the preferred manner of practicing the invention has been shown and described in detail, it will be understood I do not limit myself to the precise construction, arrangement and combination of parts set forth, and that various changes in the form, proportion and minor details may be resorted to without departing from the spirit or sacrificing any of the advantages of the invention.

Having thus described the invention what is claimed is:

1. A mine having a main hauling way, auxiliary hauling ways and working passages, a manway or safety passage substantially parallel and co-extensive in length with the main hauling way, and means for creating a current of air through the auxiliary hauling ways and working passages, said current finding its outlet through the manway and the main hauling way.

2. A mine having a main hauling way, auxiliary hauling ways and working passages, a manway or safety passage substantially parallel and co-extensive in length with the main hauling way, means for creating a current of air through the auxiliary hauling ways and working passages, said current finding its outlet through the manway and the main hauling way, and means for reversing the direction of such air current.

3. A mine having a main hauling way, auxiliary hauling ways and working passages, doors affording communication between the main hauling way and certain of the auxiliary hauling ways and working passages, a manway or safety passage substantially parallel and co-extensive in length with the main hauling way, doors affording communication between the main hauling way and the manway, other doors affording communication between the manway and certain of the auxiliary hauling ways and working passages, means for creating air currents through the auxiliary hauling ways and working passages, said currents finding their outlet through the manway and the main hauling way and means for reversing the direction of said air currents.

4. A mine having a main hauling way, auxiliary hauling ways and working passages on each side of the mine, a manway or safety passage substantially parallel and co-extensive in length with the main hauling

- way, normally closed doors affording communication between the manway, the main hauling way and the auxiliary hauling ways and working passages, an overcast in the 5 manway adjacent to the front of the mine and extending over the main hauling way, an overcast adjacent to the inner end of the mine over the main hauling way and between the manway and the auxiliary hauling 10 way and working passage on one side of the mine, a deflector or partition adjacent to the last mentioned overcast, the auxiliary hauling ways and working passages on each side of the mine at the inner end of the latter 15 being in open communication with the manway and main hauling way, and means for creating currents of air through the auxiliary hauling ways and working passages of each side of the mine, said currents finding 20 their outlet through the manway and the main hauling way.
5. A mine having a main hauling way, auxiliary hauling ways and working passages on each side of the mine, a manway or safety passage substantially parallel and co-extensive in length with the main hauling way, normally closed doors affording communication between the manway, the main hauling way and the auxiliary hauling ways 25 and working passages, an overcast in the manway adjacent to the front of the mine and extending over the main hauling way, an overcast adjacent to the inner end of the mine over the main hauling way and between the manway and the auxiliary hauling 30 way and working passage on one side of the mine, a deflector or partition adjacent to the last mentioned overcast, the auxiliary hauling ways and working passages on each side 35 of the mine at the inner end of the latter being in open communication with the manway and main hauling way, a reversible fan for creating a current of air through the auxiliary hauling way and working passage 40 on one side of the mine, a fan for creating a current of air through the auxiliary hauling way and working passage on the other side 45 of the mine, doors for reversing the direction of the current of the last mentioned fan, and a door for closing the outlet of the 50 manway.
6. A mine having a manway or safety passage co-extensive with the length of the mine, normally closed doors affording communication between said manway and the 55 various passages and working places of the mine, said manway being in open communication with the hauling and working passages at the inner extremities of the mine and means for creating a current of air 60 through the hauling and working passages, said current finding its outlet through said manway.
7. A mine having a main hauling way, a 65 manway or safety passage substantially parallel and co-extensive in length with the main hauling way, normally closed doors affording communication between the main hauling way and the manway, auxiliary hauling ways and working passages, normally closed 70 doors affording communication between the main hauling way and the various parts of the auxiliary hauling ways and working passages, an overcast over the main hauling way adjacent to its inner end and affording 75 communication between the manway and said auxiliary hauling ways and working passages, a deflector or partition arranged adjacent to said overcast, said main hauling way and the auxiliary hauling ways and 80 working passages being in open communication with the inner end of the mine beyond said deflector or partition, means for creating an air current through the auxiliary hauling ways and working passages, said 85 current finding its outlet through the manway and the main hauling way and means for reversing the direction of such current.
- In testimony whereof I hereunto affix my signature in the presence of two witnesses. 90
